UNITED STATES PATENT OFFICE.

FRANK E. BOCONSELSKI, OF SPRINGFIELD, MASSACHUSETTS.

DRILLING ATTACHMENT FOR VARIOUS CLASSES OF MACHINES.

938,113.

Specification of Letters Patent. Patented Oct. 26, 1909.

Application filed October 16, 1907, Serial No. 397,685. Renewed September 16, 1909. Serial No. 518,074.

To all whom it may concern:

Be it known that I, FRANK E. BOCONSELSKI, a citizen of the United States of America, and resident of Springfield, in the county of Hampden and State of Massachusetts, have invented certain new and useful Improvements in Drilling Attachments for Various Classes of Machines, of which the following is a full, clear, and exact description.

10 The object of this invention is to provide a mechanism which may be utilized as an attachment for various classes of machines having a rotatively driven chuck-carrying spindle or arbor, such for instance as lathes, 15 or drill presses, for drilling pluralities of holes in a piece of work in various relations and in contiguity or in comparatively wide separation, as desired, the attachment being especially available for "small work" and 20 adequately meeting the requirements in the execution of such work in shops where there may be an absence, in the equipment, for instance, of multiple spindle, and radial, drilling machines.

25 The present invention consists in an attachment comprising a body, a plurality of drill spindles adjustably carried by the body, a shaft engaged with, but rotatable independently of, the body and adapted to be 30 chucked in the lathe, drill press or other machine, gearing and connections between the said shaft and spindles for securing rotations of the latter for the rotation of the former, and furthermore,—as is especially 35 essential and important,—an extension or handle provided to the body by means of which the latter may be manually held against being rotated while the drilling attachment is being operated.

40 The invention furthermore consists in certain specific combination or arrangement of parts, and the particular construction of some of the parts, which constitute the drilling attachment, all substantially as herein- 45 after fully described and set forth in the claim.

This attachment as actually constructed, and practically used is illustrated in the accompanying drawings in which,—

50 Figure 1 is a sectional elevation, the parts in section being on the plane of the axis of the mechanism. Fig. 2 represents projected views in detail of one of the pinions of a circular series thereof, for driving one of 55 the drill spindles,—the key or spline therefor being separately shown. Fig. 3 is a sec-

tional view of one of the pinion engaged, spline grooved, shafts. Fig. 4 is a plan view of the attachment,—the annular closing cap of the hollow head or gear casing 60 being removed. Fig. 5 is a plan view showing the support for the drill spindle carrying bars, and such bars, as seen below the plane indicated by line 5—5, Fig. 1.

Similar characters of reference indicate 65 corresponding parts in all of the views.

In the drawings,—the attachment is shown as including a stock or body comprising a hollow circular or cup shaped gear casing A constructed with a detachably fastened annular cap plate A². The gear casing has, in the design shown, three radially extended integral lugs a rigidly connected with which are depending posts b supporting at their lower ends and suitably below and separated 75 from the hollow gear casing a ring shaped support B for a plurality of bars C which are adjustable on the said supporting ring in a plane at right angles to the axis of the stock or body; and these bars carry at their 80 inner ends rotatable, but endwise immovable, drill spindles b², b³ having chucks d at their lower ends for receiving drills or taps therein, and to be tightly held by the chuck d².

The drill receiving sockets, one of which 85 is represented by dotted lines at d³ in Fig. 1, are of considerable extent within the lengths of the drill spindles so that allowance is thereby afforded for a long range of adjustment of the drills, the shanks of which 90 may be inserted more or less far as desired in such sockets.

The drill spindle carrying bars C are made each with a longitudinal slot c whereby it engages about a stud f affixed to and depending from the ring support B, and is adjustable lengthwise, radially of the attachment, and also is adjustable by being swung bodily relatively to its stud for non-concentric relations of the drill spindles.

100 f², f³, represent the confining nuts for the drill spindle carrying bars.

D represents a shaft rotatably engaged in and projected beyond the upper part of the head, the lower necked down portion e thereof being fitted through the central bore through the hub extension e² of the gear casing, such portion having within the gear casing a rigidly affixed gear wheel g. The protruding screw threaded lower end of the 105 shaft D receives a clamping nut e³ thereon. The upper enlarged end portion of the shaft

D is made with a taper, as shown, whereby it is adapted to be received into various chucks, carried, for instance, in a drill press or lathe.

5   h h represent, in a circular and concentric series, shafts axially parallel with the shaft D, and fitted or journaled, axially movable, however, through bearing openings i therefor in the base of the gear casing and in the 10 cap plate thereof. The lower ends of these shafts h have shaft sections j universally joint connected thereto, which shaft sections j are also universally joint connected to the upper ends of the drill spindles b. Each 15 shaft h has a vertical spline groove k in the side thereof and each said shaft h is embraced by a pinion m, the series of such pinions being in mesh with the spur gear wheel g which is affixed on the shaft B. 20 Each said pinion, centrally circularly apertured is constructed with an internal key way 10 with recesses 12, 12, within their tops and bottoms outwardly extended from the length of the key way. 25   13 represents a straight bar like key for each pinion, made with outwardly extended opposite end lugs 14 which are accommodated in the said recesses 12 at top and bottom of the pinion, a portion of the thickness 30 of the key proper being received in the key way 10, in the pinion, while the other portion of the thickness of the key is engaged in the spline groove of the particular one of the series of shafts h in conjunction with 35 which the pinion is provided. This peculiar formation of the key is important, as subserving a desirable function. The lugs 14 hold the key against movement and prevent it being displaced and accidentally removed 40 from the device, through the top of the gear casing; it having been found that a straight key will sometimes be dislodged in this manner at critical periods of the operation of the device, thereby disabling this particular portion 45 of the machine.

The pinions are held in the gear casing against axial "shucking" or displacement, by the base and cap plate of the casing, these parts being constructed with circular 50 bosses for the most practical character of bearings.

The shafts h h will be permitted to freely have endwise movements when the bars C C are moved in various directions for adjustment, in desired arrangement or relations, of the drill spindles; and the said shafts h engaged through the hollow head and pinions therein as described and shown will never cramp the action of the universal joint 55 connections between such shafts h and the drill spindles.

It is to be particularly pointed out that the hollow head or gear casing of this drilling attachment is provided with a radial 60 handle extension G which, in the utilization

of the mechanism, will be grasped by the hand, preventing the revolution of what may be properly regarded as the body or stock of the device and assuring, under the rotation of the axial shaft D,—as carried by the 70 chuck of a drill press or lathe,—the rotations of the plurality of drill spindles for the drilling or tapping work.

As manifest, the drill spindles may be adjusted to have any arrangement in relation to each other within the scope of the mechanism, so as to drill holes in circular or other arrangement, closely to, or comparatively remote from the axial center of the device and at regular intervals, or with so irregular spacing; and in a shop not equipped with either a multiple spindle drill or a radial drill, the work required of such machines may be performed by placing this attachment in a drill press or in a lathe. 75 And in case, for instance, a plate or flange is to be drilled with, say 12 holes, by the G, may be turned so as to bring the drill spindles, four of the holes will be drilled at one presentation of the device operatively to 80 the work, and then on being withdrawn therefrom the body or head, by the handle G, may be turned so as to bring the drill spindles for presentation around to points which are relatively intermediate to those 85 first drilled, and so on until the required number of holes shall have been produced.

I claim:—

In a drilling attachment of the character described, in combination, an upwardly opening cup-shaped head, and a supporting frame for spindle carrying bars below and rigidly connected with said cup-shaped head, a driving shaft having a portion thereof concentrically engaged with and endwise immovable relatively to the said cup-shaped head and freely rotatable relatively to the latter and having a portion thereof extended upwardly therebeyond, a spur gear affixed on said shaft within the head, a plurality of pinions inclosed within said head, resting by their under faces on the latter, and in mesh with said shaft-carried spur gear wheel, a plurality of shafts parallel with said first named shaft, in concentric arrangement relatively thereto, spline engaged through said pinions, whereby they partake of rotative movements as driven by the latter and whereby they are freely endwise movable relatively to said pinions, said shafts having bearing engagements through circular apertures therefor which are provided in concentric arrangement in the under portion of said cup shaped head, a cap plate for the cup-shaped casing provided with a central aperture, for the accommodation of the first named shaft, and provided with a series of apertures in concentric arrangement thereabout, having locations concentric with the pinion axes and through and 110

above which the upper extremities of said spline engaged shafts are freely movable, said cap plate engaging the upper faces of said pinions and restraining the latter from axial displacement, and detachable means for the confinement of said cap plate on said cup shaped body.

Signed by me at Springfield, Mass., in presence of two subscribing witnesses.

FRANK E. BOCORSELSKI.
